AIR TREATING UNIT

Charles T. Waltman, Chicago, Ill., and John W. Norris,
Marshalltown, Iowa, assignors to Lennox Industries,
Inc., Marshalltown, Iowa, a corporation of Iowa

Application May 22, 1958, Serial No. 51,031

Term of patent 14 years

(Cl. D62—4)

Figure 1 is a top plan view of an air treating unit embodying our new design.

Figure 2 is a front elevational view of the unit of Figure 1.

Figure 3 is a side elevational view of the unit of Figure 2 as seen from the right hand side thereof, the left side being identical therewith.

Figure 4 is a fragmentary cross section taken along line 4—4 on Figure 2.

We claim:

The ornamental design for an air treating unit, substantially as shown and described.
